UNITED STATES PATENT OFFICE.

HENRY DALE, OF PHILADELPHIA, PENNSYLVANIA.

IMPROVEMENT IN LOOMS.

Specification forming part of Letters Patent No. **58,609**, dated October 9, 1866.

To all whom it may concern:

Be it known that I, HENRY DALE, of Philadelphia, Pennsylvania, have invented an Improvement in Looms; and I do hereby declare the following to be a full, clear, and exact description of the same, reference being had to the accompanying drawings, and to the letters of reference marked thereon.

My invention relates to improvements in that class of looms in which a number of heddles are used for operating the warp-threads, so as to produce figured fabrics; and my improvements consist, first, in the arrangement in respect to the frame and jacks of a shaft carrying a cylinder with pins or other equivalent device for operating the jacks, the said arrangement being such that the cylinder or its equivalent may be readily detached from the loom when a change of pattern is required in the fabric; second, in a certain simple arrangement of gearing, described hereinafter, for operating the said pattern-cylinder from the cam-shaft of the loom; third, in an arrangement of graduated pulleys, described hereinafter, for guiding the heddle-cords and jacks.

In order to enable others skilled in the art to make and use my invention, I will now proceed to describe its construction and operation.

On reference to the accompanying drawings, which form a part of this specification, Figure 1 is a rear view of sufficient of a loom to illustrate my improvement; Fig. 2, a side view, looking in the direction of the arrow, Fig. 1; and Fig. 3, a sectional plan on the line 1 2, Fig. 2.

A is one of the frames of a loom, in which turn the crank-shaft B and the usual cam-shaft C, the opposite journals of the said shaft turning in the opposite frame, and on the end of the crank-shaft which extends beyond the side frame, A, is secured a crank-wheel, E.

On a stationary shaft, F, secured to the side frame, A, turn a number of grooved pulleys, *a a*, over each of which passes a cord, *b*, one end of the latter being attached to one of the usual heddles of the loom, and the other end to one of a number of jacks, G, which slide in a slotted guide-plate, H, secured to the frame A, the pulleys *a a* being so graduated in size that the ends of all the cords *b* secured to the

jacks G shall be nearly parallel to each other, as shown in Fig. 1, for a purpose described hereinafter.

On the shaft C, near the frame A, is secured a pinion, *x*, the teeth of which are adapted to those of a cog-wheel, *m*, on a shaft, I, the latter turning in the frame A, and its outer end extending beyond the jacks G, and on the opposite end of the shaft C is a cog-wheel, which gears into a pinion on the shaft B, the latter wheel and pinion not being shown in the drawings.

On the outer end of the shaft I fits a detachable cylinder, J, from the face of which project pins *c c*; and to the lower ends of the jacks G are secured springs *d*, which tend to maintain the front edges of the said jacks in contact with the cylinder J.

On the rear edge of each jack, near the lower end of the same, is a projection, *e*, the purpose of which will be described hereinafter.

To an adjustable bar, *g*, on the side frame, A, is hung a lever, K, which is connected by a rod, *f*, to a pin on the crank-wheel E, and on the end of this lever is secured a bar, *n*, occupying a position at the rear of the jacks.

When the loom is in operation, the cylinder J will rotate, and a vibrating motion will be imparted to the lever K, so that the bar *n* will move up and down adjacent to the rear edges of the jacks G. So long as the front edge of a jack is in contact with the cylinder J it will not be affected by the movement of the bar *n*. When, however, one of the pins *c* comes in contact with one of the jacks and pushes the latter backward, the projection *e* of that jack will be within range of the vibrating bar, which will thus depress the jack and elevate the heddle connected with it. It will thus be seen that the operation of the heddles, and consequently the pattern of the fabric, will be regulated by the arrangement of the pins on the cylinder.

When a pattern is to be changed, the cylinder I is removed by sliding it laterally from the shaft to make way for another cylinder having pins arranged in a different manner. A plain cylinder may be used for the purpose of carrying a chain having projections, which regulate the pattern in the same manner as the pins on the cylinder.

By the arrangement described of the different-sized pulleys *a a*, each cord *b* is maintained on a line with the jack to which it is attached, as seen in Fig. 1, so that there is no tendency to draw the jacks laterally and create undue friction, as would be the case were all the cords passed over pulleys of the same size.

If desired, levers connected to the plate and to the heddle may be substituted for the pulleys and cords. An intermittent lateral, as well as a rotary, motion may also be imparted to the cylinder *I*, so as to move it alternately to and from the jacks.

The bar *n*, instead of being secured to a lever, may be arranged to slide in vertical guides adjacent to the jacks *G* without any change in the result.

Without confining myself to the precise construction and arrangement of parts herein de-

scribed, I claim as my invention, and desire to secure by Letters Patent—

1. The within-described arrangement in respect to the frame *A* and the jacks of the shaft *I*, for the reception and removal of the cylinder *J*, or its equivalent.

2. The combination and arrangement on the loom of the cam-shaft *C*, wheels *x* and *m*, and shaft *I*, as specified.

3. The combination and arrangement of the graduated pulleys *a a*, the jacks *G*, and the heddle-cords, as set forth.

In testimony whereof I have signed my name to this specification in the presence of two subscribing witnesses.

HENRY DALE.
